(57) **CLAIM**

The ornamental design for a work light, as shown and described.

DESCRIPTION

FIG. 1 is a perspective view of a work light, showing my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left-side elevation view thereof;

FIG. 7 is a right-side elevation view thereof;

FIG. 8 is a perspective view of a modified embodiment of the design shown in FIGS. 1-7;

FIG. 9 is a front elevation view of the work light of FIG. 8;

FIG. 10 is a rear elevation view of the work light of FIG. 8;

FIG. 11 is a top plan view of the work light of FIG. 8;

FIG. 12 is a bottom plan view of the work light of FIG. 8;

FIG. 13 is a left-side elevation view of the work light of FIG. 8; and,

FIG. 14 is a right-side elevation view of the work light of FIG. 8.

The broken lines shown represent unclaimed subject matter and form no part of the claimed design.

1 Claim, 10 Drawing Sheets
